UNITED STATES PATENT OFFICE.

MAYER DOPPELMAYER, OF SHERMAN, TEXAS.

LINIMENT.

SPECIFICATION forming part of Letters Patent No. 438,063, dated October 7, 1890.

Application filed July 26, 1890. Serial No. 359,918. (No specimens.)

To all whom it may concern:

Be it known that I, MAYER DOPPELMAYER, a citizen of the United States, residing at Sherman, in the county of Grayson and State 5 of Texas, have invented a new and useful Medical Compound, of which the following is a specification.

The invention relates to improvements in medical compounds.

10 The object of the present invention is to provide a medical compound or liniment for the alleviation and cure of wounds, especially those occasioned by barb-wire fences, burns, bruises, sprains, rheumatism, frost-bites, and 15 hemorrhoids on man or beast.

The compound consists of the following ingredients combined in the proportions stated, viz: refined cotton-seed oil, four table-spoonfuls; cotton-seed oil, (third quality,) one and 20 one-half table-spoonful; carbolic acid, one and one-half table-spoonful; coal-oil, nine and one-half table-spoonfuls; turpentine, nine and one-half table-spoonfuls; tallow, six table-spoonfuls; beeswax, two table-spoonfuls.

25 The ingredients are compounded as follows: The tallow and beeswax are melted separately and then mixed while both are in a heated condition. Immediately after this, agitate the mixture and add the refined cotton-seed oil, 30 coal-oil, turpentine, carbolic acid, (dissolved,) and the third quality of cotton-seed oil, each in their order named. The ingredients are mixed in an open vessel, the contents of which are well stirred while compounding the mixture.

35 After being thoroughly mixed the whole is put up in bottles and should be well shaken before using.

For torn and cut skin, flesh, leather, and

barb wire cuts take a small cloth and saturate with the liniment and apply to the wound 40 (without rubbing) three times a day, if in summer, and twice if in winter. The wound should not be tied up or covered or in any way bandaged, and water should not be employed for washing, but always clean with the 45 liniment. Where the wound is a deep one, clean out first by tying a long narrow piece of cloth to a switch and turning the switch until the entire cloth, with the exception of a small end, is in the wound. Then pull out 50 the cloth. This should be repeated twice a day until the wound stops running. Always use the liniment after the wound is cleaned as above and continue to use the liniment with a syringe until the wound is healed. For 55 frost-bites use at night until perfectly cured. For hemorrhoids dilute by adding one-half the quantity of butter (without salt) or sweet-oil and apply to the parts. For bruises rub lightly, applying the liniment with the hand 60 morning and night. For sprains and rheumatism rub the liniment in well with the hand night and morning.

What I claim is—

The herein-described medical compound, 65 consisting of cotton-seed oil, carbolic acid, coal-oil, turpentine, tallow, and beeswax, as set forth.

In testimony that I claim the foregoing as my own I have hereto affixed my signature in 70 presence of two witnesses.

MAYER DOPPELMAYER.

Witnesses:

T. B. HUGGINS,
IKE EXSTEIN.
